ELECTRIC SHOE POLISHER

Gordon Florian, Fairfield, Conn., assignor to The Iona Manufacturing Company, Inc., Manchester, Conn., a corporation of Connecticut

Filed Apr. 5, 1965, Ser. No. 84,608

Term of patent 14 years

(Cl. D9—2)

FIGURE 1 is a top plan view of an Electric Shoe Polisher embodying my new design;

FIGURE 2 is a right side elevational view thereof;

FIGURE 3 is a front end view thereof;

FIGURE 4 is a bottom plan view thereof;

FIGURE 5 is a left side elevational view thereof; and,

FIGURE 6 is a rear end view thereof.

The broken line showing of the brush has been omitted in FIGS. 1, 3, 4, 5 and 6 for convenience of illustration.

The dominant features of my design reside in the portions shown in full lines.

I claim:

The ornamental design for an Electric Shoe Polisher, as shown and described.
